UNITED STATES PATENT OFFICE.

SPENCER G. NEAL, OF LOS ANGELES, CALIFORNIA, ASSIGNOR TO CALIFORNIA VALVE AND AIR BRAKE COMPANY, OF LOS ANGELES, CALIFORNIA, A CORPORATION OF CALIFORNIA.

COMPENSATING VALVE.

1,089,577.

Specification of Letters Patent. Patented Mar. 10, 1914.

Application filed July 29, 1913. Serial No. 781,836.

To all whom it may concern:

Be it known that I, SPENCER G. NEAL, a citizen of the United States, residing in the city of Los Angeles, State of California, 5 have invented a new and useful Compensating Valve, of which the following is a specification.

The compensating valve which forms the subject matter of this invention is adapted 10 to a great variety of uses, but is more particularly intended as a means to regulate the supply of air under pressure to air braking systems for railways.

The present invention has for its principal 15 object, an improved compensating valve that will not fail to maintain a predetermined pressure in a train pipe, such train pipe pressure in present practice being reduced (not maintained) when leaks occur 20 in the train pipes or fittings.

This compensating valve will operate successfully in conjunction with the engineer's valve of present braking systems with but slight alteration of said valve. Moreover, 25 this compensating valve automatically maintains a predetermined pressure in a train pipe during service, lap, and running positions; in this particular this invention is an improvement over the feed valve in use at 30 the present time, because said feed valve is capable of furnishing air to the train pipe in moderate quantities only, and only during such times as the engineer's valve is in running position.

35 Referring to the accompanying drawings, which illustrate the invention: Figure 1 is a diagrammatic view illustrating the application of this compensating valve to a well-known air braking system. Fig. 2 is a vertical mid-section of the compensating valve. Fig. 3 is a plan view of a disk, which is inserted in a well-known braking valve to adapt same to coöperate with this compensating valve. Fig. 4 is a view, the sectional 40 part of which illustrates certain changes in a well-known engineer's valve to adapt same to coöperate with the compensating valve, which forms the subject matter of this invention. Fig. 5 is a mid-section of the compensating valve, the valve operating parts being shown in a different position from that illustrated in Fig. 2.

45 Referring in detail to the drawings, 1 in a general way designates the compensating valve, (see Fig. 1) 2 the engineer's valve

and 3 the main storage reservoir for supplying braking air to the train pipe. The well known main supply pipe 4 leads from the storage reservoir 3 to the brake valve 2; a branch pipe 5 leads from the brake valve 2 50 to the main train pipe 6. Pipe 4 may be provided with the well known cut-out valve 7. The brake valve 2 is connected with the usual equalizing reservoir 8 by means of an equalizing pipe 9. Pipe 5 is provided with 55 valve 11. In order to connect the compensating valve 1 with these well known parts, a supply pipe 12 is run from the reservoir pipe 4 to the compensating valve 1, said pipe 12 preferably being provided with a cut-out 60 valve 14; and an equalizing reservoir pipe 15 is run from the compensating valve 1 to the equalizing reservoir 8 or to the pipe 9, which is in communication with said equalizing reservoir 8. Said pipe 15 is preferably 65 provided with a cut-out valve 16; pipe 17 is also added to connect the compensating valve to the main train pipe 6, said pipe 17 preferably being furnished with a cut-out 70 valve 18.

The braking apparatus which has thus far been described, relates to the engine only and it is to this part of the braking apparatus of the train that this invention pertains, but in practical operation the braking 75 action on each car of the train is affected.

Referring now more particularly to Fig. 4, this view shows the well known engineer's brake valve altered somewhat in the sectioned portions to adapt the same to coöperate with this compensating valve. 22 is the usual train pipe piston chamber, the piston being removed therefrom, and a combined metallic and leather gasket or disk 23 then being placed over said chamber 22 to 80 make an air tight seal between the equalizing chamber 24, and said train pipe chamber 22. The reason for inserting said gasket 23, is that the well known piston (not shown) which ordinarily occupies chamber 22, 85 would not make an absolutely air tight closure between the chambers 22 and 24. The main reservoir-supply passage 25, the train pipe supply passage 26 and the train pipe connecting passage 27 are not altered from 90 the standard equipment, but equalizing discharge valve outlet 28 is closed by screw plug 29, as shown in Fig. 4.

Referring now in detail to the construction of the compensating valve shown in 110

section in Figs. 2 and 5, the casing for said valve preferably comprises an upper cap 31, having an upward tubular extension 32, and the lower cap 33. Within the casing formed by said caps 31 and 33 is a diaphragm device designated in a general way by the numeral 35, said device comprising the diaphragm proper 36, the base diaphragm support 37, having the tubular upward extension 38 projecting centrally therefrom, said extension 38 being externally threaded near its base to receive an internally threaded upper diaphragm support or clamping member 39, which is screwed down upon the diaphragm 36. Said tubular extension 38 closely fits the interior of the cap extension 32 and said extension 38 is preferably contracted throughout its upper portion, as shown in Fig. 5, in order to reduce the size 10 of the stuffing box 41. The upper end of said extension 38 is provided with radial ports or vents 42. Within the tubular extension 38 is a valve device comprising a valve stem 43, having a winged middle portion 44, terminating at its lower end in a release valve 45, below which is another winged portion 46 terminating at its lower end in a train pipe supply valve 47. The valve device just described, its winged portions 44 and 46, and its valves 45 and 47 are formed in one piece, the various parts of which necessarily move in unison. Said valve device is provided at its upper end with a stop nut 51, screwed on to the upper 15 end thereof and retained by lock nut 52. Said stop nut 51 is at times engaged by the upper end of the tubular extension 38 to lift the valve device. It will be seen that there is an annular clearance or passage 53 around the stem 43, and that this passage in combination with the air space provided by the winged portion 44, permits the air to pass from the valve 45, when open, to the upper end of the valve device and out the vents 42. 20 Upon the upper end of the cap extension 32 is screwed a housing or cap 54, provided with vents 55 so that air escaping from the vents 42 can pass to the outer atmosphere. The downward movement of the valves 45 and 47 is limited by an adjustable stop nut 56, which is screwed into an extension 57, of sufficient size to admit the valves 45 and 47 together with the valve stem 43. Said adjustable nut 56 is retained in the adjusted position by 25 lock nut 58.

The diaphragm device 35 divides the interior of the casing into two compartments, an upper chamber 61, which forms an equalizing chamber, and a lower chamber 62 30 which forms the train pipe chamber. The air from the main reservoir 3 (see Fig. 1) is conducted by the branch pipe 12 to an inlet passage 63, thence to the interior of the extension 57 beneath valve 47, so that when 35 said valve 47 is open the air can enter the

train pipe chamber 62. The winged portion 46 between valves 45 and 47 moves inside of guiding sleeve 64 formed within the casing as shown in Figs. 2 and 5. The valve casing members 31 and 33 already referred to, 40 are provided with flanged portions between which is clamped the diaphragm proper 36, said flanged portions being held together by the cap screws 65. The equalizing chamber 61 is provided with a port 61^a, from which the pipe 15 leads to the equalizing reservoir 8. Train pipe chamber 62 is provided with a train pipe passage or port 62^a, which communicates with train pipe branch 17. 45

Disk 23 (see Figs. 3 and 4) is provided 50 with an aperture 25^a to register with supply passage 25, with an aperture 26^a to register with train pipe supply passage 26, and with the well known equalizing passage 70. These 55 openings furnish outlets to all the passages and ports of the well known engineer's brake valve, the piston chamber alone being closed at its upper end and thereby separated from chamber 24.

Operation: This compensating valve performs all the functions of the equalizing discharge valve and its piston (said piston being dispensed with and removed from the piston chamber 22 on the engineer's valve as already stated), and in addition to 90 such functions, this compensating valve performs certain other functions which will hereinafter be described. The engineer's valve proper will perform all of its well known functions, and maintain its various 95 positions as before, namely, full release, running, service, lap and emergency positions. The charging of the train pipe is caused, as is well known in present braking systems of the standard type, by placing the engineer's 100 valve in the full release position in order quickly to charge the train pipe; said engineer's valve being placed at the running position, as in present practice, as soon as the desired maximum train pipe pressure has 105 been obtained. The train pipe having thus been charged to the required pressure and the equalizing reservoir 8, also being charged to an equality with the train pipe pressure, the result will be that the pressure in the 110 equalizing chamber 61, which is in communication with the equalizing reservoir 8, will be the same as the train pipe pressure in the train pipe chamber 62 of the compensating valve, said chamber 62 being in direct communication with the train pipe through the pipe 17. With the pressure as just described, in order to make a reduction of the train pipe pressure the brake valve 2 is placed in the service position, thereby releasing air from the equalizing reservoir 8 to the atmosphere to any desired amount, and thus through pipe 15 releasing the pressure in the equalizing chamber 61 of the compensating valve below the pressure in the lower train 115 120 125 130

pipe chamber 62 of said compensating valve. The result of this change of pressure will be to allow the excess pressure in chamber 62 on the lower side of diaphragm 36 to raise the diaphragm device 35 and the parts connected therewith, to the position shown in Fig. 5, thus opening the release valve 45 to release train pipe air through passage 53 and vents 42 and 55. When the train pipe pressure in the train pipe chamber 62 has thus been reduced beneath the pressure in equalizing chamber 61, said diaphragm device 35 and the parts carried thereby will move back to the lap position, thus closing the release valve 45 and cutting off further escape of train pipe air. If instead of reducing the pressure in the equalizing reservoir, as has just been described, the engineer's valve was operated in such a manner as to raise the pressure in the equalizing reservoir 8, and therefore in the equalizing chamber 61 of the compensating valve, the result would be a reverse operation of the compensating valve, the pressure in equalizing chamber 61 exceeding that in train pipe chamber 62 and causing the valve 47 to open, as shown in Fig. 2, thus supplying air to the train pipe by way of branch pipe 17, which leads from the train pipe chamber 62 of the compensating valve.

It is evident that any reduction of pressure in the train pipe chamber 62 will operate the compensating valve in the same manner as an increase of pressure in the equalizing chamber 61. Such reduction may be caused by leaks in the train pipe and also by the operation of the triple valve to supply the desired amount of air to the brake cylinder for service application.

The adaptability of this compensating valve to furnish air pressure to the train pipe for all service applications when using the patented triple valve just referred to, eliminates the necessity for augmenting the train line capacity for service applications and materially reduces the element of time now required for charging the auxiliary reservoir, because air for service applications is not secured from the auxiliary reservoir for service braking.

I claim:

1. In a compensating valve, a casing, a diaphragm dividing said casing into two compartments, one of said compartments forming an equalizing chamber, and the

other of said compartments forming a train pipe chamber, a valve device located centrally of said diaphragm and operated thereby, said valve device comprising a valve element adapted to control communication from the main reservoir to said train pipe chamber, and another valve element adapted to control communication from said train pipe chamber to the outer atmosphere.

2. In a compensating valve, a casing, a diaphragm device dividing said casing into two compartments, one of said compartments being an equalizing chamber and the other of said compartments being a chamber in communication with the train pipe, there being a passage extending through the central portion of said diaphragm device, a valve device located in said passage, said valve device comprising a valve element adapted to control communication from the main reservoir to said chamber in communication with the train pipe, and another element adapted to control communication from said train pipe chamber through said central passage to the outer atmosphere.

3. In a compensating valve, a casing, a diaphragm device dividing said casing into two compartments, one of said compartments being an equalizing chamber and the other of said compartments being a chamber in communication with the train pipe, said diaphragm device having a hollow extension projecting centrally therefrom through the equalizing chamber and casing at that side of the device, a valve device extending through said hollow extension and provided with a shoulder movable into and out of engagement with the end of said hollow extension to move the valve device, a valve element carried by said valve device to control the entrance of air from the train pipe chamber into said passage, and another valve element carried by said valve device to control communication between the main reservoir and said train pipe chamber.

In testimony whereof I have hereunto signed my name in the presence of two subscribing witnesses at Los Angeles, in the county of Los Angeles and State of California, this 23rd day of July, 1913.

SPENCER G. NEAL.
